UNITED STATES PATENT OFFICE

2,002,779

CONNECTER CAP

Francis C. Kollath, Chicago, Ill., assignor, by
mesne assignments, to Cutler-Hammer, Inc.,
Milwaukee, Wis., a corporation of Delaware

Application October 21, 1929, Serial No. 401,049

13 Claims. (Cl. 173—361)

My invention relates to connector caps and more especially to shock absorbing caps in which the body is made of a suitable rubber-like material similar to that shown in my copending application Serial Number 296,309 and which is ordinarily used in connection with extension cords for making separable connection with attachment plugs and receptacles.

Connector caps having a body made of moulded insulation are easily damaged and often broken by being dropped on cement floors or by other rough usage. In connector caps of the shock absorbing type, it has been necessary to mould the interior, including the blades and attached conductors, into the rubber base or to insert and remove these interiors by the use of a special tool for stretching the base sufficiently to allow the removal and insertion of the interior.

In my invention, I have overcome these objections and it is one of the objects to provide a connector cap which will be shock absorbing and in which the connector blades and their support may be easily removed for wiring and inserted without the use of any tools.

Another object is to provide a connector cap which may be easily wired and in which the connector blades are rigidly secured in spaced relation and which is provided with a suitable strain relief.

A further object is to provide an article of manufacture of few parts, easy to assemble, cheap to manufacture, and which will not easily get out of order.

Further objects will appear from the detailed specification to follow and from the appended claims.

Realizing that my invention may be varied in its physical embodiment without departing from the spirit of the invention, I desire it to be understood that the specific construction herein shown is to be taken as illustrative and not in a limiting sense.

In the accompanying drawing in which an embodiment of my invention is shown,

Fig. 1 is a longitudinal section through a connector cap embodying my invention, the interior being shown in full lines.

Fig. 2 is an end view of the device as illustrated in Fig. 1.

Fig. 3 is a transverse sectional view taken on a line corresponding to line 3—3 of Fig. 1.

Fig. 4 is a sectional view of the base with the interior removed and taken on a line corresponding to line 4—4 of Fig. 1.

Fig. 5 is a perspective view of one of the connector blades.

Referring now to the drawing in detail the embodiment of my invention as illustrated comprises a handle 1 made of a soft, flexible, elastic, rubber-like material preferably moulded and having an enlarged portion 2 with a chamber 3 therein. The passage 4 extends through the handle and communicates with the chamber 3 for the passage of suitable conductors 5. The chamber 3 is preferably provided with tapered side walls 6. The bottom of the chamber forms the shoulder 7 against which the insulating base 8 is seated.

The base 8 may be made of any suitable insulating material such as sheet fibre and is supported in the slots 9 in the side walls of the chamber 3.

The slots 9 extend to a point slightly below and adjacent the front end of the cap, the overhanging portion 10 of the handle serving to retain the insulating base 8 with the connector blades or prongs 11 supported securely in the chamber 3.

These connector blades 11 are secured to the insulating base 8 by means of the rivets 12, and are provided with the binding screws 13 for the conductors 5.

The connector blades or prongs 11 are mounted on opposite sides of the base 8 and are located parallel to each other. These prongs are off-set from their bases 15 as clearly shown in Fig. 5 so that they will be disposed opposite from each other and spaced from the base 8 as clearly shown in Fig. 3.

The contour of the base 8 is such as to fit snugly within the slots 9, the upper portion of the slots being enlarged at 14 to receive the riveted end portions 15 of the blades 11.

The enlarged portion 14 of each slot 9 is formed for the purpose of receiving the base portion 15 of each prong 11. The slots 9 with their enlarged portions 14 therefore snugly engage the base member 8 and the outer edges of the bases 15, Fig. 3.

The inner surface of each of these portions 15 is knurled as shown at 16 thus providing a suitable means to prevent the turning of the blade under the rivets 12.

The base 8 is provided adjacent its lower end with the opening 17 through which the conductors pass in opposite directions as shown in Fig. 1, thus providing an efficient strain relief to prevent the wires being pulled from the binding screws 13.

It will be noted that the interior is securely

held in position in the handle and supported in the slots 9 by the elastic properties of the base.

When it is desired to remove the interior from the handle in order to secure the conductors to the terminals, the enlarged portion is placed between the thumb and finger at points opposite the binding screws 13. At the same time the blades and base 8 are pushed to the right, the base taking the form shown by the dotted lines in Fig. 2 and allowing the upper edge of the base 8 to be tilted and removed from the corresponding slot 9. The opposite side of the base is removed from its corresponding slot in the same manner.

In inserting the interior, it is only necessary to press the enlarged end 2 of the base together slightly, the tapered contour of the base 8 allowing it to be forced downwardly and into the chamber 3 of the rubber handle until the base slips into the slots 9 as shown in Fig. 1.

20 It is sometimes desirable to dispense with the binding screws 13 in which case the conductors may be soldered directly to the connector blades 11.

Having thus described my invention, what I claim and desire to secure by Letters Patent is:

1. A shock absorbing connector comprising a handle made of a soft, elastic, rubber-like material, a flat, thin, longitudinal, removable base longitudinally arranged in said handle and supported in position in the handle by the elastic properties of the handle, connector members supported by said base and removable therewith, said connector members being fastened to the flat sides of the base and on opposite sides thereof, said connector members also having offset parts to space the connectors a proper distance apart to be receivable in a cooperating electric member, and conductor terminals on said members.

2. A shock absorbing connector comprising a handle made of a soft, elastic, rubber-like material, a longitudinal, flat, thin, removable base in said handle and extending longitudinally thereof, said base being supported in the handle by the elastic characteristics of the base, and offset connector members supported by said base and on each side thereof.

3. A shock absorbing connector comprising a handle made of a soft, elastic, rubber-like material and having a chamber therein to receive a base, a removable base in said chamber and secured therein by the elastic properties of the handle, spaced connector members supported by said base, said base having sides spaced from the handle and being removable from the handle by applying pressure against the sides of said handle where the base is spaced from the handle.

4. A shock absorbing connector comprising a handle made of a soft, elastic, rubber-like material and having a chamber therein, a comparatively thin, tapered, insulating base supported in slots in the side walls of said chamber said slots ending at a point below the face of said handle, said handle having an overhanging portion of the handle forming a retaining means for said base, and spaced connector pins supported on said base.

5. An electric connector comprising an insulated flat thin longitudinal base having flat sides and contact prongs fastened to said flat sides on opposite sides of the base, said prongs being offset to operable spaced positions, and a soft rubber casing totally encasing the base.

6. An electrical connector comprising a casing made of elastic material having oppositely disposed longitudinal grooves therein, a relatively

thin but relatively rigid insulating base slidingly and removably received in said grooves and longitudinally disposed in said casing, means for holding said base in said grooves, and electrical contacts connected with said base and having portions thereof projecting from said casing.

7. An electrical connector comprising a flexible rubber casing having oppositely disposed longitudinal grooves therein, a relatively thin but relatively rigid insulating base arranged in said grooves and longitudinally disposed in said casing, said casing having integral shoulders overhanging and engaging the base for holding the base in the grooves, and electrical contacts connected with said base and adapted to be retained by the latter in spaced and insulated relationship to each other.

8. An electrical connector comprising a flexible rubber casing having a chamber therein, a relatively thin elongated base longitudinally arranged in said casing and retained therein by the elastic properties of the base and contact prongs fixed to said base on opposite sides thereof, said contact prongs being off-set from the base to properly space them from each other.

9. An electrical connector comprising a flexible rubber casing having a chamber therein, diametrically disposed longitudinal slots in said chamber, a flat base arranged in said slots and engaging the bottom of the chamber, contact prongs fastened to opposite sides of the base and off-set therefrom, and an integral overhanging ledge on said casing and engaging the base for holding the base in the casing.

10. In an electric connector comprising a casing formed of elastic material and having oppositely disposed longitudinal grooves therein, a flat elongated base arranged in the grooves, and connector prongs fastened to opposite sides of the base and extending a predetermined distance beyond the end of the casing, said base being maintained in position in the grooves by the elastic properties of the casing, there being spaces on opposite sides of the flat base, said base being removable from the casing when pressure is applied on the casing at the spaces on the sides of the base whereby the casing will become elongated and permit removal of the base.

11. An electrical connector comprising a flexible rubber casing having a chamber therein, a relatively thin but relatively rigid elongated base longitudinally arranged within said chamber and retained therein by the elastic properties of the base, and a plurality of combined contact and wiring terminal members associated with said base and retained in position thereby.

12. An attachment plug cap comprising a relatively thin but relatively rigid plate of insulating material, a pair of contact prongs rigidly attached to said base on opposite sides thereof respectively, said prongs having the free end portions thereof offset from said base to afford a proper space relationship therebetween, a flexible rubber casing having a recess into which said base is forcibly insertable edgewise to extend longitudinally of said casing, and a pair of conductors extending into said casing and electrically connected to said contact prongs, said base having an opening formed therein and into which the conductors may be threaded in reverse directions respectively to provide a strain relief for the electrical connections between the latter and said contact prongs.

13. An attachment plug cap comprising a cap body formed of a relatively soft, elastic, rubber-

like insulating material and having a relatively deep recess opening to one end thereof, the longitudinal wall of said recess being provided with a pair of grooves arranged in diametrically opposed relationship to each other, said grooves terminating in a common plane spaced inwardly from the open end of said cap body to provide stop shoulders formed integrally with the latter, a relatively thin but relatively rigid base 10 of insulating material forcibly insertable into said recess and longitudinally disposed therein, the side and end edges of said base being adapted to be snugly accommodated by the walls of said grooves whereby said base is positively retained in assembled relation to said cap body, a pair of one-piece combined plug jack and wiring terminal members supported by said base, the plug jack portions of said members being offset from said base and extending outwardly from said cap body in properly spaced relation, said cap body having an extension formed integrally therewith to provide a hand-grip, and said extension having a cord passage 10 extending therethrough and opening to said recess. 5

FRANCIS C. KOLLATH.

CERTIFICATE OF CORRECTION.

Patent No. 2,002,779.

May 28, 1935.

FRANCIS C. KOLLATH.

It is hereby certified that error appears in the printed specification of the above numbered patent requiring correction as follows: Page 2, first column, lines 63 and 64, claim 4, strike out the words "of the handle"; line 74, claim 6, for "opositely" read oppositely; and page 3, second column, line 1, claim 13, for "groves" read grooves; and that the said Letters Patent should be read with these corrections therein that the same may conform to the record of the case in the Patent Office.

Signed and sealed this 24th day of September, A. D. 1935.
